UNITED STATES PATENT OFFICE.

EDWIN F. HARDEY, OF KANSAS CITY, MISSOURI.

APPLIANCE FOR LIGHT, HEAT, AND MASSAGE TREATMENT.

1,228,669.

Specification of Letters Patent.

Patented June 5, 1917.

Application filed January 22, 1917. Serial No. 143,650.

To all whom it may concern.

Be it known that I, EDWIN F. HARDEY, a citizen of the United States, residing at Kansas City, in the county of Jackson and State of Missouri, have invented certain new and useful Improvements in Appliances for Light, Heat, and Massage Treatment, of which the following is a specification.

My invention relates to a new and useful device whereby the person may be simultaneously massaged, treated with radiant heat, and also, with penetrating light rays, and my object is to provide a novel device of this character which is simple in construction and operation, well adapted for the purpose intended, and which can be manufactured at small cost.

The device can be used to advantage in treating various complaints, such, for instance, as improper circulation of the blood, neuralgia, headache, indigestion, lumbago-sciatica, nervousness, etc.

In order that the invention may be fully understood, reference will now be made to the accompanying drawings, in which:

Figure 1 is a side elevation, partly in section, of the device assembled and ready for use.

Fig. 2 is a broken plan view, partly in section, of certain parts disclosed by Fig. 1.

Fig. 3 is a plan view, partly in section, with a comb substituted for the roller disclosed by Figs. 1 and 2.

Fig. 4 is a side elevation partly in section, of one type of applicator and a bridge to support said applicator.

Figs. 5 and 6 are enlarged details of different forms of applicators adapted to be used in connection with the invention.

In carrying out the invention, I employ a parabolic reflector 1 adapted to concentrate light and heat rays upon a comparatively limited area of the person. Said reflector 1 has a lamp socket 2 provided with a cable 3, adapted to communicate with a suitable source of electricity. In practice the free end of the cable 3 is, preferably, provided with a plug, not shown, whereby it may be connected to an ordinary incandescent lamp socket.

5 designates an incandescent lamp arranged within the reflector 1 and removably connected to the socket 2. Said lamp 5 is of sufficient power to cast rays of light and heat of such degree as to prove beneficial in the treatment of the complaints above enum-

erated and such others as usually respond to treatment of this character.

7 designates a bridge adapted to be secured at its ends to the reflector 1. As said bridge 7 is at times subjected to considerable pressure it is desirable to firmly secure it to the reflector 1, so the opposite sides of the latter are notched as indicated at 8 to receive shoulders 9 on the ends of the bridge, which has rearwardly-extending lugs 10 with threaded holes to receive screws 12, extending through opposite sides of the reflector 1 to secure said bridge thereto.

As indicated by Figs. 1 to 3, inclusive, the intermediate portion of the bridge member 7 is comparatively narrow and projects forwardly beyond the front edge of the reflector 1 to obstruct as little as possible the light and heat rays projected from the lamp 5 by said reflector 1.

In Figs. 1 and 2, the bridge member 7 is provided with an applicator in the form of a roller 14 consisting, preferably, of soft rubber and adapted more particularly for massaging the body. Said roller 14 is journaled in bearings 15, extending forwardly from a shield 16, arranged in rear of the roller 14 to protect the same from the light and heat rays, which in some instances is sufficient to damage the soft rubber from which said roller 14 is preferably constructed. The shield 16 is removably secured to the bridge 7 by two screws 17, also adapted to pass through openings 18 in said bridge 90 to secure thereto another form of applicator.

Before proceeding further it might be well to state that the term "applicator" used throughout the specification is intended to apply to any of the applicators shown on the drawings or such others as may be attached to the bridge 7, as it is apparent that various forms of applicators can be employed without departing from the spirit or scope of the invention.

As disclosed by Fig. 4, it will be seen that the bridge 7 has a central opening 19 adapted to receive the threaded stem 20 of any of the applicators 21, 22 and 23 which may be readily substituted for each other when desired. As the applicators 21 and 23 are made, preferably, of soft rubber, a shield in the form of a disk 16 is interposed between such applicators and the bridge 7, to prevent the heat and light rays from the lamp 5 striking said applicators and possibly damaging the same.

The applicator 21 is adapted more particularly for massaging the face and scalp. The applicator 23 is intended more especially for massaging the face, and the applicator 22, which consists preferably of hard rubber, is particularly adapted for use in massaging the neck, shoulders and spinal column.

24 designates an applicator in the form of 10 a comb, which may be used to advantage in treating the hair and scalp, and also in drying the hair after a shampoo. As disclosed by Fig. 3, the comb 24 is removably secured to the bridge 7 by the screws 17, which are 15 threaded into the openings 18.

All of the applicators are of such size as not to materially interfere with the projection of light and heat rays from the lamp 5 by the reflector 1.

20 For convenience in manipulating the device to secure the massaging effect and to apply the light and heat to the various parts of the person, the reflector 1 is provided with a handle 26 removably secured 25 thereto by a threaded shank 27.

From the foregoing description, it is apparent that I have produced a device whereby the person can be massaged and at the same time receive the benefit of radiant 30 heat from the powerful electric light concentrated by the reflector 1, the penetrating rays of which stimulate the large blood vessels and the large nerve trunks, it being well understood that heat assists in stimulating 35 circulation, while the light rays destroy germs.

Having thus described my invention, what I claim and desire to secure by Letters Patent, is:

1. In a device of the character described, 40 the combination with an electric lamp and a reflector for projecting the light and heat rays from said lamp, of a rubber applicator, means for supporting said applicator in front of the reflector, and a shield for protecting the applicator from the light and heat rays.

2. In a device of the character described, 45 the combination with an electric lamp and a reflector for projecting the light and heat rays from said lamp, of an applicator, and a bridge secured at its ends to the reflector and projecting forwardly therefrom to support the applicator in advance of the reflector.

55 3. In a device of the character described, the combination with an electric lamp and a reflector for projecting the light and heat rays from said lamp, said reflector having two oppositely-disposed notches therein, a bridge having shoulders to fit into the notches and lugs to fit against the sides of the reflector, thumb screws for engaging the reflector and said lugs, and an applicator supported in front of the reflector by the bridge.

In testimony whereof I affix my signature, in the presence of two witnesses.

EDWIN F. HARDEY.
